BUFFER FAN HANGER

Seymour James Stewart, New Orleans, La.

Application June 12, 1937, Serial No. 147,850

1 Claim. (Cl. 248—18)

My invention relates to ceiling fan hangers, particularly to hangers including a buffer device or/and self-staying means.

One of the objects of the invention is to provide a self-staying fan hanger, to dispense with unsightly guy lines and brackets conventionally used to prevent oscillation of a motor fan.

Another object of the invention is to provide a buffer fan hanger that will insulate shocks caused by motor action and prevent objectionable noises.

Another object is to provide a hanger easy to make, easy to set up, easy to take down, simple, practical and economical.

15 These and other objects are attained by means illustrated and described in the following specification, and defined in appended claim.

For the purpose of disclosure, I show two only of many forms that may embody the invention. 20 In one of these the fan hanger is mounted on the head of a lag screw set in a joist, beam or the like, and having its head and a short part of its body extending below the ceiling. In the other form of the invention, the hanger is connected to a threaded pipe projecting through the 25 ceiling.

Both of the illustrative forms of the invention preferably include a ceiling or wall support-fastener, or means for connecting the hanger to a ceiling or wall support; a motor fan connector, or means for connecting the hanger to some part or member of a fan or like motor driven implement; self-staying means and buffer means. These parts thus named for convenient reference, will hereinafter be more fully described.

In the drawing:

Fig. 1 is a horizontal section, on the line I—I, Fig. 2, and view of a fan hanger mounted on the head of a lag screw.

40 Fig. 2 is a vertical section, on the line II—II, Fig. 1, and view showing the lag screw head seated and the hanger locked thereon.

Fig. 3 is a limited vertical section on the line III—III, Fig. 2.

45 Fig. 4 shows a bottom view of a modified form of the invention in which the hanger is connected to a threaded pipe protruding the ceiling.

Fig. 5 is a vertical section on the line V—V, Fig. 4, and view.

50 Fig. 6 is a horizontal section on the line VI—VI, Fig. 5.

Fig. 7 shows a limited vertical section on the line VII—VII, Fig. 5.

55 Fig. 8 is a limited vertical section on the line VIII—VIII, Fig. 5.

Referring to Figs. 1, 2 and 3, which show a self-stayed and buffer fan hanger mounted and locked on the head of a lag screw: 9 is a ceiling or wall support fastener, or means for connecting a hanger to any suitable support, and 10 is a motor fan connector, or means for connecting a hanger to the stem or other member of a fan. 11 is the head of a lag screw and 12 is its seat on the hanger. The wall or ceiling plate 13 freely telescopes the body of the lag screw, washer like, and is provided with a circular concentric retainer ridge 14. These parts co-operate to hold the hanger and lag screw against co-relative rotation and substantially co-axial in the preferred form. Freeways 15 and 16, respectively for the body and head of the lag screw, facilitate mounting and demounting the hanger. Lock shoulders 17 operate to secure the head of the lag screw in place and the longitudinal bore 18 and cross freeway facilitate electric wiring. 19 is any suitable buffer means which is preferably enclosed in the housing 20, to insulate shocks and jolts and prevent noises thereby caused.

In the modified form of the invention, Figs. 25 4—8, 21 is a stationary member adapted to being mounted on a pipe projecting from the ceiling and to demountably provide a seat or support for the hanger. 22 shows a shoulder or retainer that co-operates with removable keeper 30 23 to lock the hanger in place. The said keeper may consist of a U shaped member having one or both of its terminals threaded and provided with nuts as shown; or the keeper may comprise a single bolt or pair of bolts, such as carriage 35 bolts with heads cut to fit the freeway 24. The latter facilitates seating the head of the support-fastener 25, which in preferred form is a member of hollow rectangular section, with an enlarged base flaring to match the fan-connector 40 26 to which it is contiguously assembled but separated and adjacently surrounded by any suitable buffer means 27. The housing 28, preferably of metal, may enclose the said buffer means and assembled parts. The electric wiring 45 is facilitated by the longitudinal hollow and the cutaway part 29 of the support fastener.

It will be understood that the buffer material or means, although shown as sheet rubber, may comprise rubber or the like vulcanized in suitable molds, or raw rubber filling the housing and vulcanized in place, or any device including the like of springs arranged to comprise an equivalent buffer hook-up.

Shape and form of the hanger are not essen- 55

tial, but that shown is now believed to be preferable.

A self-staying hanger may be constructed in one piece, including the support-fastener 9 and the fan-connector 10; or having in one piece said support fastener, fan-connector and ceiling plate 13 all made in one piece, and provided with the longitudinal bore and freeways equivalently as shown; and it may be round or of any other desired shape.

When sheet rubber is used as the buffer means, it may be convenient to stamp or cut the housing blank to match the buffer sheet blank, then to fold and crimp both together, as shown in Fig. 1.

Mounting a hanger of the form shown in Figs. 1-3, the lag screw should be backed or screwed from its seat to provide about $\frac{1}{4}$ inch play between the head of the lag screw and ceiling. Then, with the body and head of the lag screw in the respective freeways of the hanger, the latter may be raised to permit the screw head to pass the shoulders 17 and dropped into its seat. Then turning the hanger, using a wrench if required, will cause the screw to jam the plate 13 against the ceiling and the parts will co-operate to hold the hanger and fan against oscillation caused by motor action.

It will be understood that by reversing the

foregoing procedure, the hanger may be easily demounted.

The foregoing forms of the invention, presently believed best, have been selected for disclosure, with the understanding that the invention is not limited to the details shown; for example, the ceiling plate 13 may be secured in place by a plurality of ordinary screws and provided with means equivalent to those shown for demountably supporting, insulating and staying a motor fan.

I claim the following combinations, and other combinations to these equivalent:

Means for mounting a ceiling fan comprising: a flanged headed support adapted to be secured to the ceiling, a laterally engageable connectable sleeve adapted to be demountably held on the head of said support, co-operating means on said headed support and said sleeve to prevent relative turning therebetween, a fan attaching sleeve surrounding said first mentioned sleeve, and a sleeve of rubber-like material interposed between said two sleeves for connecting them together and acting as a vibration absorbing means to prevent vibration incident to the operation of said fan being transmitted to said ceiling.

SEYMOUR JAMES STEWART.
